Robert McDonald

UNITED STATES PATENT OFFICE.

EDWARD B. LIMLE, OF CINCINNATI, OHIO, ASSIGNOR, BY MESNE ASSIGNMENTS, TO UNITED-XPEDITE FINISHING COMPANY, OF BERWICK, MAINE, A CORPORATION OF MAINE.

FINISHING DEVICE.

1,351,177.

Specification of Letters Patent. Patented Aug. 31, 1920.

Application filed March 5, 1918. Serial No. 220,493.

To all whom it may concern:

Be it known that I, EDWARD B. LIMLE, a citizen of the United States, residing at Cincinnati, in the county of Hamilton and State 5 of Ohio, have invented certain Improvements in Finishing Devices, of which the following description, in connection with the accompanying drawings, is a specification, like reference characters on the drawings indicating like parts in the several figures.

My invention relates to finishing devices, it having particular reference to devices for burnishing or polishing portions of shoes, 15 as the sides of the heels.

The heels of shoes, especially those for women, differ greatly in height and form, some being excessively curved and these curves varying from season to season, even 20 in the same style of shoe. An object of this invention is to provide a burnishing or finishing device which is to a large extent self-conforming and which may, in any event, readily be adjusted to different dimensions 25 and forms of work.

To the above end, a feature of the invention consists of a revolute member by which a series of work-engaging members is carried and which is of such character and 30 so mounted that it may yield under pressure applied to the work-engaging members. I prefer to attain this yield by making the revolute carrier member itself flexible, there being shown a series of such members 35 upon each of which a series of finishing members is hung.

In order that the finishing members may thus yield to conform to the surface operated upon, in addition to the yield of the 40 carrier member and at the same time to exert a positive rubbing action, as a feature of the invention each finishing member is mounted on two carrier members, so that said finishing member is free to move, and 45 yet after a certain movement under the pressure of the work is held against further retreat. I have shown for this purpose openings in the finishing members through which the carrier members pass, these openings 50 being elongated and converging toward the axis of revolution.

As a further feature, finishing members mounted in a series upon the carrier are tapered at adjacent sides from their work-engaging surfaces inwardly. This enables 55

them to yield or tip laterally with considerable freedom better to conform to the curvature of the work, yet maintaining as nearly as possible a continuous work-engaging surface.

In addition to the flexibility of the carrier members and the yield of the work-engaging means, as means for adapting the device to different forms and dimensions of the work, a feature of the invention is found in relatively adjustable supports for the carrier members. Such an adjustment may cause the same length of carrier member to assume different curves during its revolution. Moreover, the supports preferably have attaching means for carrier members of different lengths. This is here disclosed as consisting of slots in the supports opening outwardly, yet so inclined in the direction of revolution that they resist displacement of 75 the carrier members by centrifugal force.

Other features will be developed in the following detailed description, taken in connection with the accompanying drawing,—

Figure 1 of the latter being a view of my 80 improved finishing device, partly in side elevation and partly in central vertical section;

Fig. 2 a full end elevation looking from the left in Fig. 1;

Figs. 3 and 4 details in side and edge elevation of one of the finishing members, and

Fig. 5 showing in detail the securing means for the ends of the carrier members.

As a support for the active portions of the device, I have illustrated a sleeve 10 adapted to receive the shaft of a burnishing or other finishing machine, to which it may be secured to rotate by a set screw 12. One end of the support is provided with a head furnished by an annular flange 14 integral with or otherwise fixed upon the sleeve, while near the opposite extremity the sleeve carries a movable head consisting of an annular flange 16 projecting from the inner end of a collar 18. The collar is held against rotation upon the sleeve, while being adjustable through a considerable range toward and from the head 14, by a spline and groove indicated at 20. A set screw 22 threaded through the collar serves to lock it in the position to which it may be adjusted longitudinally of the sleeve.

In the heads 14 and 16 are pairs of aligned openings shown as slots 23 opening through 110

the peripheries of the heads. The direction of rotation of the device in use is as indicated by the arrow in Fig. 2 and the slots 23 are inclined forwardly or in the direction 5 of rotation. In opposite pairs of slots are secured carrier members 24 in a regularly spaced circumferential series, there being twenty here shown and consisting of sections 10 of wire cable or the like, of such flexibility as to allow it to curve outwardly under the action of the centrifugal force generated by its revolution and that of the members which it carries and to yield inwardly under the pressure of the work. Fixed on the end of 15 each section of the cable and lying within the slots are externally threaded fittings 26, which are clamped to the heads 14 and 16 by nuts 28 to retain the cable sections in place. This construction permits different 20 lengths of cables to be introduced through the ends of the slots by merely loosening the securing nuts, while their outward displacement when clamped in place is resisted, not alone by the frictional engagement of the nuts with the walls of the head but also by the pressure of the fittings 26 against the edges of the slots 23, there being a considerable 25 component of the displacing force which is radial and therefore not effective 30 to move the fittings along the slots. Moreover, since the inclination of the slots is in the direction of rotation, the pressure of the work tends to force the fittings toward the bottoms of the slots and still further insure 35 their retention.

The cables 24 carry the work-engaging or 40 finishing members proper. In the present embodiment of the invention these finishing members are in the form of disks 30, each provided with elongated openings or slots 32, 32 to receive adjacent cables. The slots 32 extend from points near the opposite sides of each disk toward one another, being inclined inwardly in the direction of the 45 axis of revolution. As illustrated, their adjacent extremities are separated by a portion 34 of the disk. When the sleeve 10 is rotated, the revolution of the cables and disks causes them to assume the positions 50 shown in Fig. 1, the cables occupying catenary curves, while the disks extend radially outward with edges of their widened outer work-engaging portions 36 in contact with the sides of the adjacent disks of each series 55 which they overlap. The series of disks, considered circumferentially of the support, are in close proximity to one another, this arrangement tending to give a work-engaging surface as nearly as possible continuous. 60 At this time the inner ends of the slots at 34 are forced against the pairs of adjacent carrier cables. As the work is pressed against the engaging surfaces 36, both the cables and the disks may yield to enable the 65 operating surface of the device, considered

as a whole, to accommodate itself to variations in contour, yet offering enough resistance to give an effective polishing action. This resistance is due in part to centrifugal force and to the rigidity of the cables, and in part results from the two-point support offered by the slots 32, 32 which prevents the disks from turning upon the cables too freely. As they turn, however, under sufficient pressure, the outer end of one of the 70 slots of each disk contacts with its cable, stopping the rotary shift of the disk to give a positive rubbing in addition to the self-conforming action. The work-engaging surface of each disk is of maximum width 75 considered longitudinally of the cable, the sides 38 tapering inwardly therefrom, preferably to points 40 beyond the cable. This arrangement facilitates the lateral yield of the disks; they having room to tip or shift about fulcrums 80 furnished by the contact of their outer edges at 42 with adjacent disks.

In using the device, such lengths of cables, each with their series of disks varying in accordance with the length, are attached to 90 the supporting heads, that when the sleeve 10 is rotated by the shaft of the finishing machine to which the device is applied, the work-engaging surface will best adapt itself to the particular form and size of heel 95 or other work to be operated on. The revolution of the cables and disks holds them in the relation illustrated, and then under the pressure of the work they yield by virtue 100 of the flexibility of the cables, of the bodily movement of the disks radially of the sleeve and their rotation about axes within their peripheries through the shifting of the slots along the cables, and of their lateral tipping. Yet the shifting is so resisted by the 105 centrifugal force, by the contact of the cables with the ends of the slots in the disks and by the pressure of the companion elements, that the engaging faces strike the work effective rubbing blows to polish it. 110 When heels of another form or height are to be polished, it is a simple matter to remove the cables and disks by loosening the nuts 28 and replace them by others which may be better adapted for the purpose, the 115 head 16 being correspondingly adjusted if necessary.

Having thus described my invention, what I claim as new and desire to secure by Letters Patent of the United States is:

1. In a finishing device, a revoluble carrier, and a series of work-engaging members mounted thereon, the carrier being constructed and arranged to yield under pressure upon any of the work-engaging members.

2. In a finishing device, a revoluble carrier, and work-engaging members mounted thereon, the carrier being constructed and arranged to bend as a whole under the

- action of centrifugal force and at particular portions under pressure upon the work-engaging members.
3. In a finishing device, a revolute flexible member, and a plurality of work-engaging members movable about the flexible member to conform to the work.
4. In a finishing device, a revolute flexible member, and a plurality of work-engaging members each provided with an elongated opening through which the flexible member extends.
5. A finishing device comprising a rotatable support, a flexible member secured at its extremities only to separated points upon the support, and a series of finishing members carried by the flexible member.
6. A finishing device comprising a rotatable support, flexible members extending between separated points upon the support in a circumferential series, and a series of finishing members carried by each flexible member.
7. In a finishing device, adjacent yieldable revolute members, and a finishing member mounted to move upon both of said revolute members.
8. In a finishing device, adjacent revolute flexible members, and a finishing member yieldably mounted upon both said revolute members.
9. In a finishing device, plural revolute members, and a finishing member having a plurality of elongated openings through which the revolute members extend.
10. In a finishing device, revolute members, and a finishing member having a plurality of elongated openings inclined with respect to one another through which the revolute members extend.
11. In a finishing device, revolute members, and a finishing member having a plurality of elongated openings converging toward the axis of revolution through which the revolute members extend.
12. In a finishing device, a revolute carrier, and a plurality of finishing members mounted upon the carrier in close proximity to one another and being tapered at their adjacent sides from their work-engaging surfaces toward their inner edges.
13. In a finishing device, a revolute flexible member, and a plurality of tapered members loosely mounted upon the flexible member.
14. In a finishing device, a revolute flexible member, and a plurality of tapered members having elongated openings near their reduced extremities through which the flexible member extends.
15. In a finishing device, revolute members, and a plurality of finishing members tapered inwardly from their work-engaging surfaces and each having a plurality of openings to receive the revolute members.
16. In a finishing device, revolute members, and a plurality of finishing members tapered inwardly and having elongated openings converging toward the tapered ends to receive the revolute members.
17. In a finishing device, adjacent revolute flexible members, and a plurality of finishing members tapered inwardly from their work-engaging surfaces and each having a plurality of openings to receive the revolute members.
18. A finishing device comprising rotatable supporting members relatively adjustable toward and from one another, a flexible carrier extending between the supporting members, and finishing members mounted upon the carrier.
19. A finishing device comprising rotatable supporting members, and revolute finishing means carried by the supporting members, there being slots opening outwardly through the peripheries of the supporting members to receive the finishing means, said slots being inclined to resist the displacement of the finishing means under the influence of centrifugal force.
20. A finishing device comprising rotatable supporting members, and revolute finishing means carried by the supporting members, there being slots forwardly inclined in the direction of rotation opening outwardly through the peripheries of the supporting members to receive the finishing means.
21. A finishing device comprising a rotatable member having opposite heads, one of which is movably mounted upon the member, means for fixing the movable head in the position to which it may be adjusted, a circumferential series of carriers extending between the heads, and finishing members mounted upon the carriers.
22. A finishing device comprising a rotatable member having opposite heads, one of which is movably mounted upon the member, means for fixing the movable head in the position to which it may be adjusted, flexible members extending between the heads, and finishing members loosely mounted upon the flexible members.
23. A finishing device comprising a rotatable member having opposite heads, one of which is movably mounted upon the member, means for fixing the movable head in the position to which it may be adjusted, flexible members extending between the heads, and a series of disks carried by each flexible member.
24. A finishing device comprising a rotatable member having opposite heads, one of which is movably mounted upon the member, means for fixing the movable head in the position to which it may be adjusted, flexible members extending between the heads, and a series of disks carried by each

flexible member and being tapered from curved work-engaging faces to points beyond the flexible members.

25. A finishing device comprising a rotatable member having opposite heads, one of which is movably mounted upon the member, means for fixing the movable head in the position to which it may be adjusted, flexible members extending between the heads, and a series of disks each provided with a slot to receive a flexible member.

26. A finishing device comprising a rotatable member having opposite heads, one of which is movably mounted upon the member, means for fixing the movable head in the position to which it may be adjusted, flexible members extending between the heads, and a series of disks each provided with slots to receive a plurality of flexible members.

27. A finishing device comprising a rotatable member having opposite heads, one of which is movably mounted upon the member, means for fixing the movable head in the position to which it may be adjusted, flexible members extending between the heads, and a series of disks each being provided with two slots converging inwardly and receiving adjacent flexible members.

30. 28. A finishing device comprising a sleeve having a head fast thereon, a head movable upon the sleeve, both heads being provided

with openings, means for securing the movable head in adjusted position, cables passing through the openings in the opposite heads, and work-engaging disks hung upon the cables.

29. A finishing device comprising flexible rotatable supports, and a plurality of successive circumferential series of finishing members mounted on the supports, the members of each circumferential series being closely placed with respect to one another and overlapping the sides of both adjacent series.

30. A finishing device comprising a rotatable support, and a plurality of successive circumferential series of disks, the disks of each series having their edges closely placed with respect to one another and the sides of the disks overlapping the sides of the adjacent series.

31. A finishing device comprising a rotatable support, a plurality of successive circumferential series of finishing members, the members of each circumferential series being closely placed with respect to one another and overlapping the sides of both adjacent series, and flexible means for supporting the members.

In testimony whereof I have signed my name to this specification.

EDWARD B. LIMBLE.
